DESIGN FOR A BOTTLE OR SIMILAR ARTICLE

Félicie Eugénie Amélie Wanpouille Bergaud,
Paris, France

Application June 20, 1939, Serial No. 85,587

Term of patent 7 years

To all whom it may concern:

Be it known that I, Félicie Eugénie Amélie Wanpouille Bergaud, a citizen of the French Republic, residing at Paris, France, have invented a new, original, and ornamental Design for Bottles or Similar Articles, of which the following is a specification, reference being had to the accompanying drawing, forming part thereof.

or similar article showing my new design; Figure 2 is a side view thereof. The opposite side of the bottle is substantially the same as the front elevational view as shown in Figure 1.

I claim:

The ornamental design for a bottle or similar article, substantially as shown and described,

FÉLICIE EUGÉNIE AMÉLIE
WANPOUILLE BERGAUD.
